REFRIGERATION

Arnold D. Siedle, Canton, Ohio, assignor to The Hoover Company, North Canton, Ohio, a corporation of Ohio

Application October 10, 1938, Serial No. 234,143

10 Claims. (CL 62—119.5)

This invention relates to the art of refrigeration and particularly to a novel absorption refrigerating system which is constructed and arranged automatically to freeze blocks of ice in a body of water to a predetermined size and then to discontinue the production of refrigeration for ice freezing purposes for a period of time sufficient to allow previously formed ice blocks to float to the surface of the water from which they have been formed.

Previous refrigerating systems have been proposed in which the production of ice and the melting period thereof are regulated by various forms of thermostatic control mechanisms which may be within or without the refrigerating system. However, all such previous constructions necessitate the use of control means which add considerably to the cost and complexity of the apparatus.

Accordingly, it is a principal object of the present invention to provide a refrigerating system of the above referred to character in which the production and melting periods of the ice are automatically regulated without the intervention of any special form of control means within or without the system and without necessitating the provision of any moving parts in order to effect the desired control of the apparatus.

More specifically, it is an object of this invention to provide a refrigerating system of the character above referred to which will automatically store refrigerant liquid enroute from the condenser to the evaporator for a period of time sufficient to permit previously formed ice blocks to melt free of the walls of the water container and to discharge such accumulated liquid periodically into the evaporating zone in order to produce another crop of ice blocks.

It is a further object of one form of the invention so to arrange the refrigerant accumulating means that the same operates to interrupt the flow of pressure equalizing medium through the evaporator of the refrigerating system to accelerate the melting of previously formed ice blocks.

Other and more specific objects of the invention will become apparent as the description proceeds when taken in connection with the accompanying drawings, in which:

Figure 1 is a diagrammatic representation of a refrigerating system embodying the present invention.

Figure 2 is a transverse sectional view of the evaporator structure of the present invention.

Figure 3 is a fragmentary diagrammatic illustration of a modified form of the invention.

Referring now to the drawings in detail and first to Figure 1 thereof, there is illustrated an absorption refrigerating system of the three-fluid type embodying a boiler B, an analyzer D, a rectifier R, a tubular air-cooled condenser C, an evaporator E, a gas heat exchanger H, a tubular air-cooled absorber A, a liquid heat exchanger L, a gas burner G for heating the boiler B, a solenoid valve S for controlling the gas burner and a circulating fan F which is driven by an electrical motor M. These elements are suitably connected by various conduits to form a plurality of gas and liquid circuits constituting a complete refrigerating system to which reference will be made in more detail hereinafter.

The above described refrigerating system will be charged with a suitable refrigerant, such as ammonia, a suitable absorbent, such as water, and a suitable inert pressure equalizing medium, preferably a dense inert gas such as nitrogen.

The application of heat to the boiler B generates refrigerant vapor from the strong solution therein contained. The refrigerant vapor so liberated passes upwardly through the analyzer D in counterflow relationship to strong solution flowing downwardly therethrough. Further refrigerant vapor is generated in the analyzer from the strong solution by the heat of condensation of absorption solution vapor which is generated in the boiler. The refrigerant vapor formed in the analyzer is conveyed therefrom to the upper portion of the condenser C by means of a conduit 11 which includes the air-cooled rectifier R. The rectifier R causes condensation of any vapor of absorption solution which may pass through the analyzer. The refrigerant vapor supplied to the condenser is liquefied therein by heat exchange relationship with the surrounding air and is discharged in liquid phase through a conduit 12 into a syphon chamber 13. A small vent conduit 14 is connected between the chamber 13 and the outer pass of the gas heat exchanger H.

The liquid collecting in the syphon chamber 13 is periodically discharged therefrom, in a manner to be described in detail hereinafter, through a syphon conduit 15 into the bottom portion of the evaporator E. The exact construction of the evaporator E will be described in detail hereinafter; for the present it is sufficient to note that the liquid refrigerant discharged from the conduit 15 into the evaporator evaporates into a propelled stream of inert gas flowing therethrough to produce refrigeration. The rich mixture formed in the evaporator is conveyed therefrom through the conduit 17 into the inner path of

the gas heat exchanger H from which it is conveyed through the conduit 18 into the bottom portion of the absorber A.

The rich pressure equalizing medium refrigerant vapor mixture flows upwardly through the absorber A in counterflow relationship to weak solution flowing downwardly therethrough. The refrigerant vapor content of the mixture is absorbed in the solution and the resulting lean gas is conveyed from the upper portion of the absorber into the suction inlet of the circulating fan F by a conduit 19. The lean gas is placed under pressure in the fan F and is discharged therefrom into the outer path of the gas heat exchanger H through a conduit 22. The lean gas is then conveyed from the outer path of the gas heat exchanger H to the bottom portion of the evaporator E through a conduit 23.

The lean solution formed in the boiler by the generation of refrigerant vapor is conveyed therefrom to the upper portion of the absorber A through a conduit 24, the inner path of the liquid heat exchanger L, and a conduit 25. It is apparent that the upper end of the absorber is at an elevation above the normal liquid level prevailing in the boiler-analyzer system wherefore some means must be provided in order to elevate the lean solution into the absorber. For this purpose, a small gas bleed conduit 26 is connected between the lean gas discharge conduit 22 of the circulating fan F and the conduit 25 below the liquid level normally prevailing therein whereby the lean solution is elevated into the absorber by gas lift action. The lean solution flows downwardly through the absorber by gravity in counterflow relationship to the rich pressure equalizing medium refrigerant vapor mixture in the manner described heretofore. The refrigerant vapor content of the mixture is absorbed in the absorption solution and the heat of absorption is rejected to the surrounding air by fins mounted on the exterior wall of the absorber vessel. The strong solution formed in the absorber is conveyed from the bottom portion thereof to the upper portion of the analyzer D by means of the conduit 28, the outer path of the liquid heat exchanger L, and the conduit 29.

The burner G is supplied with gas through a gas conduit 30 which is governed by the solenoid valve S. The burner G is provided with any suitable form of safety cut-off mechanism which will operate automatically to discontinue the supply of gas thereto whenever there is complete failure of flame at the burner. A small by-pass 31 is provided around the solenoid valve S in order to maintain a small pilot or igniting flame on the burner G.

Electrical energy is supplied to the apparatus from a suitable source of supply represented by the wires 33 and 34. The wire 33 connects directly to one terminal of a thermostatic control mechanism 35 which will be mounted to be responsive to the temperature of the air within the refrigerating storage compartment. Any suitable or desired form of thermostatic switch may be provided, but preferably the mechanism will include a manually operable temperature adjusting mechanism. The other terminal of the thermostatic control 35 is connected directly to the solenoid S by means of a wire 36. The motor is connected to the wire 36 by means of a wire 31. The other line wire 34 connects directly to the motor M and is connected to the solenoid valve S by means of a wire 38. As a result of this arrangement the energization of the motor M

and the burner G is under the complete control of a single box-temperature responsive thermostatic mechanism, and are normally energized and de-energized simultaneously.

Referring now to Figures 1 and 2 the evaporator construction will be described in detail. The lean gas conduit 23 and the syphon conduit 15 each communicates with a horizontally positioned coil 40 which is mounted in the upper portion of a heavily insulated fast-freezing compartment 41—indicated in dotted lines in Figure 1. A heat conducting plate 42 separates the coil 40 from the storage portion of the compartment 41. The compartment 41 will be provided with any suitable form of insulated door structure not shown. The free end of the coil structure 40 communicates with a riser conduit 43 which joins a horizontally positioned evaporator ice-freezing conduit 44. The conduit 44 terminates in a riser conduit 45 which joins a second ice-freezing conduit 46 positioned directly above the conduit 44. The conduit 46 communicates with a horizontally positioned ice-freezing conduit 47 through a rear cross-connecting conduit 48. The conduit 47 is horizontally positioned in spaced relationship with the conduit 46. The conduit 47 communicates with a riser conduit 49 which is parallel to the riser 45 and opens into a horizontally positioned ice-freezing evaporator conduit 50. The ice-freezing evaporator conduit 50 is positioned in the same plane with and parallel to the ice-freezing evaporator conduit 44. The ice-freezing evaporator conduit 50 is connected directly to the rich gas discharge conduit 17. A liquid drain conduit 52 is connected between the gas outlet portion of the conduit 50 and the gas inlet portion of the conduit 40 after extending downwardly below the plane of the conduit 40 to form a liquid gas seal.

A drain conduit 55 opens into the top portion of the gas discharge end of the conduit 40 and connects to the rich solution conduit 29.

Each of the ice-freezing conduits 44, 46, 47 and 50 is provided with a plurality of spaced heat conducting pads 56 which are adapted to receive the slightly tapered side walls 57 of a water tank 58—shown in dotted lines in Figure 1. The water tank 58 rests upon the top wall of the insulated compartment 41 with the side walls 57 thereof in firm thermal contact with the freezing pads 56. The arrangement of the tank and evaporator is such that the tank may be removed from the evaporator by sliding it forwardly or by lifting it upwardly as may be desired.

The operation of this form of the invention is as follows: Assuming that the apparatus has not been operating the temperature within the refrigerating chamber will have risen to cause the thermostat 35 to energize the circulating motor M and the solenoid valve S to supply gas to the burner G. Under these conditions, refrigerant vapor will be generated and will ultimately find its way through the conduit 12 into the syphon chamber 13. The liquid refrigerant will accumulate in the syphon chamber 13 until it shall have reached a depth sufficient to charge the syphon conduit 15. Once the syphon conduit 15 is charged it will syphon out all refrigerant previously collected in the chamber 13 and all refrigerant discharged thereinto until the liquid level within the chamber 13 has lowered sufficiently to break the seal on the syphon. The capacity of the conduit 15 is larger than the capacity of the conduit 12 in order that the conduit 15 may ultimately empty the chamber 13 to break

the seal and to discontinue the discharge of refrigerant therethrough. The vent conduit 14 serves to purge the condenser C of incondensable products and to equalize the pressure in the conduit 23 and the chamber 13.

The liquid refrigerant discharged through the conduit 15 meets a propelled stream of gas which is circulated through the evaporator by the circulating fan F. The liquid refrigerant so discharged into the evaporator conduit 40 flows into the recirculating drain 52 to fill the lower U-shaped portion thereof and to form a liquid column in the longer leg of the conduit 52 above the level of its point of connection with the coil 40 sufficient to balance the pressure differential between the conduits 40 and 50. This will seal the conduit 52 to prevent the inert gas from bypassing therethrough and will allow liquid to flow downwardly therethrough without interference from an upwardly flowing gas stream. Once the drain 52 is sealed the velocity of flow of the gas through the evaporator is increased and the remaining liquid discharged by the siphon 15 is propelled through the evaporator by the gas stream as it is evaporating to produce refrigeration. Any liquid refrigerant not evaporated in the conduit 40 is then propelled by the gas stream through the conduits 43, 44, 45, 46, 47, 48, 49 and 50, respectively, in all of which conduits evaporation occurs to produce refrigeration.

The liquid is propelled by the frictional drag exerted thereon by a relatively high velocity stream of nitrogen which drags or sweeps the liquid through the evaporator as it is evaporating. The broad invention of propelling the liquid refrigerant by the inert gas is disclosed and claimed in the co-pending application of Curtis C. Coons and William H. Kitto, Serial No. 386,395, filed April 2nd, 1941.

During initial operation of the system a very large portion of the refrigerant will evaporate in the conduit 40 thereby rapidly lowering the temperature within the compartment 41. Once the temperature of the compartment 41 is lowered relatively little refrigeration is required therefor even when foodstuffs or frozen desserts and the like are placed in the chamber 41 because there is substantially no heat loss through the wall thereof. Any liquid refrigerant which may not evaporate prior to the time at which it reaches the conduit 17 is discharged through the conduit 52 into the evaporator coil 40 to be re-circulated through the evaporator.

The above described operation of the apparatus will continue until such time as the conduit 15 shall have emptied the chamber 13 sufficiently to break the siphon seal, whereupon liquid refrigerant will again begin to collect in the chamber 13. The liquid refrigerant in the evaporator is continuously recirculated therethrough until it is substantially entirely evaporated. The pads 56 are so proportioned that the quantity of liquid discharged through the conduit 15 will be sufficient to freeze ice blocks of a predetermined size on the interior side walls of the tank 58 wherever such walls are in direct thermal contact with one of the freezing pads. After the siphon seal is broken and the residual liquid refrigerant in the evaporator has evaporated, refrigeration will not be produced and the previously formed ice blocks will melt free of the interior walls of the tank and float to the surface of the water therein contained. The time interval required for the liquid refrigerant discharged from the condenser to charge the siphon conduit 15 is ample to in-

sure that the ice blocks previously formed will have melted free of the interior walls of the tank. Therefore, when the discharge conduit 15 again becomes operative a fresh crop of ice blocks will be formed in the water tank.

This operation will continue for as long as the control mechanism 35 maintains the energization of the solenoid valve S and the circulating motor M. The air within the refrigerating compartment is cooled by contact with the exposed walls of the tank 58 which are extensive. The temperature of the walls of the tank 58 is normally maintained above the freezing point of water wherefore there is no frost formation thereon and the air within the refrigerating compartment is not unduly dried. Any frost which forms on the various exposed ice freezing evaporator conduits during the refrigerating cycle will melt free thereof during the ice melting cycle and may be collected in any suitable tray or may simply be allowed to evaporate into the air within the refrigerating compartment.

The recirculating conduit 52 need not be charged after the initial operation of the system as the refrigerant therein contained will not evaporate appreciably into the inert gas after the siphon conduit has become inoperative.

The above described refrigerating system liquefies and discharges liquid refrigerant into the siphon chamber substantially continuously and the refrigerant liquid alternately collects in that chamber and is then discharged therefrom at a relatively rapid rate into the evaporation zone. By the provision of the recirculating drain 52 the rather large amount of liquid refrigerant discharging through the conduit 15 is not wasted. It is simply continuously recirculated through the evaporator until it has evaporated to produce refrigeration. The freezing period of the apparatus extends over into what would normally be the melting period during which liquid refrigerant is again collected in the chamber 13 to recharge the siphon conduit 15. This is a desirable feature for the reason that the freezing period for the ice blocks will normally be longer than the period required for the same to melt free of the inner walls of the water tank 58.

Referring now to Figure 3, there is disclosed a modified form of the invention. This form of the invention is designed and intended to be utilized with the refrigerating system disclosed in Figure 1, therefore only such portions of the apparatus has been illustrated as will be necessary to delineate the difference between the construction illustrated in Figures 1 and 3. Certain portions of the apparatus disclosed in Figure 3 are identical with parts illustrated in Figure 1 and are therefore given the same reference characters primed.

In this form of the invention the rich gas discharges from the conduit 60, which communicates with the ice-freezing evaporator conduit 50', into the top portion of a siphon chamber 61. A rich gas discharge conduit 62 connects the inner passage of the gas heat exchanger H' with the lower portion of the siphon discharge chamber 61. The conduit 62 extends upwardly in a loop an appreciable distance above its point of connection with the chamber 61. The siphon discharge conduit 15' connects to the conduit 40' as before.

The operation of this form of the invention is substantially the same as the operation of the form of the invention disclosed in Figures 1 and 2 except in the following particulars. During the

ice melting cycle of the apparatus the liquid refrigerant discharging through the conduit 12' will accumulate in the lower portion of the chamber 61 and will eventually seal the inlet to the conduit 62, thereby stopping the inert gas flow through the evaporator. This stoppage of inert gas flow through the evaporator will accelerate ice melting and will positively insure that there is no production of refrigeration due to residual liquid in the evaporator during normal ice melting periods.

In order that this apparatus may come into operation reasonably quickly after the siphon becomes operative, the siphon in this case is of larger capacity than the siphon described in connection with Figure 1 in order that it may lower the liquid level in the siphon chamber to permit inert gas flow through the evaporator. Also the siphon 15' is provided with a U-shaped portion extending downwardly below its point of connection to the conduit 40' similar to the U-shaped traps in the conduits 52 and 52'. This is necessary in order to prevent by-passing of the inert gas from the relatively high pressure conduit 40' into the relatively low pressure chamber 61. The quantity of liquid in the evaporator is too large to be evaporated on one cycle of operation thereof, therefore there is a continuous circulation of liquid refrigerant through the evaporator and the recirculating drain 52'. The apparatus is so proportioned that refrigeration will be produced by recirculated liquid refrigerant substantially up to the time the collecting liquid seals the inlet to the inert gas conduit 62. The duration of this period will be sufficient to form ice blocks of the desired predetermined size.

The present invention provides a simple highly efficient absorption refrigerating system constructed and arranged alternately to produce ice within a large body of water and then to permit previously formed ice to melt free of the containing walls of the water tank whereby the various ice blocks may float to the surface of the water to be ladled therefrom as needed. This is accomplished without the intervention of control means of any character whatsoever excepting only of course the accumulating siphon tank which is absolutely independent of any thermally responsive mechanism, contains no moving parts, and is fully automatic in operation.

The refrigerating effect may be discontinued as desired either by eliminating the supply of liquid refrigerant to the evaporating zone or by utilizing the collection of liquid refrigerant to block inert gas flow through the evaporator.

This invention regulates the production of ice automatically in relation to the demand therefor as follows: During periods of warm weather the rate of heat loss through the box increases which causes the box temperature responsive thermostat to cycle more frequently with consequent increase in the rate of production of ice; however, it is during periods of warm weather that the demand for ice is greatest; therefore the demand in production of ice is automatically geared to the demand therefor by the ambient temperature.

While the invention has been illustrated and described in detail it is not to be limited thereto as various changes may be made in the construction, arrangement and proportion of parts without departing from the spirit of the invention or the scope of the appended claims.

I claim:

1. Refrigerating apparatus comprising an

evaporator, means for propelling an inert gas through said evaporator, means for supplying refrigerant liquid to said evaporator, the arrangement being such that the refrigerant is circulated through said evaporator by the impetus of the inert gas, means for storing refrigerant enroute to the evaporator and for intermittently discharging predetermined quantities of the stored refrigerant into the evaporator, and means for collecting liquid refrigerant which has traversed said evaporator under the impetus of the inert gas and for returning such liquid refrigerant to said evaporator for recirculation therethrough.

2. Absorption refrigerating apparatus comprising an evaporator, liquid refrigerant producing means, means for intermittently discharging a predetermined quantity of liquid refrigerant into said evaporator comprising a container, means for conveying liquid refrigerant from said producing means to said container, and a siphon connecting said container and said evaporator arranged to become operative when the liquid level in said container reaches a predetermined level and then to drain said container, means for circulating an inert gas through said evaporator with sufficient velocity and pressure to circulate liquid refrigerant through said evaporator, and means for collecting liquid refrigerant which has traversed said evaporator and for returning such liquid refrigerant to said evaporator for recirculation therethrough.

3. Absorption refrigerating apparatus comprising an evaporator, liquid refrigerant producing means, means for intermittently discharging a predetermined quantity of liquid refrigerant into said evaporator comprising a container, means for conveying liquid refrigerant from said producing means to said container, and a siphon connecting said container and said evaporator arranged to become operative when the liquid level in said container reaches a predetermined level and then to drain said container, the discharge rate of said siphon being greater than the rate at which liquid is supplied to said container, and means for circulating an inert gas through said evaporator.

4. Absorption refrigerating apparatus comprising an evaporator, liquid refrigerant producing means, means for intermittently discharging a predetermined quantity of liquid refrigerant into said evaporator comprising a container, means for conveying liquid refrigerant from said producing means to said container, and a siphon connecting said container and said evaporator arranged to become operative when the liquid level in said container reaches a predetermined level and then to drain said container, means for circulating an inert gas through said evaporator, said container being serially connected to said evaporator for flow of inert gas therethrough and arranged to block such flow when a predetermined quantity of liquid has collected therein, and means arranged to convey liquid refrigerant from a part of said evaporator having a high refrigerant vapor concentration to a part of said evaporator having a low refrigerant vapor concentration.

5. Absorption refrigerating apparatus comprising means for producing refrigerant vapor, a condenser, an insulated compartment, a water container, a freezing coil having portions in heat transfer relationship with said compartment and said container, means for intermittently supplying refrigerant discharged from said condenser to said freezing coil, and means for propelling

an inert gas through said coil to circulate the liquid refrigerant therethrough as it is evaporating to produce refrigeration.

6. Absorption refrigerating apparatus comprising means for producing refrigerant vapor, a condenser, an insulated compartment, a water container, a freezing coil having portions in heat transfer relationship with said compartment and said container, means for intermittently supplying refrigerant discharged from said condenser to said freezing coil, means for propelling an inert gas through said coil to circulate the liquid refrigerant therethrough as it is evaporating to produce refrigeration, and said intermittently operative refrigerant liquid supply means including means constructed and arranged to obstruct the flow of inert gas through said coil during periods when refrigerant is not supplied thereto.

7. Absorption refrigerating apparatus comprising an evaporator, liquid refrigerant producing means, means for intermittently discharging a predetermined quantity of liquid refrigerant into said evaporator comprising a container, and a siphon connecting said container and said evaporator arranged to become operative when the liquid level in said container reaches a predetermined level and then to drain said container, the discharge rate of said siphon being greater than the rate at which liquid is supplied to said container, and means for circulating an inert gas through said evaporator, said container being serially connected to said evaporator for flow of inert gas therethrough and arranged to block such flow when a predetermined quantity of liquid has collected therein.

8. Absorption refrigerating apparatus comprising an evaporator, liquid refrigerant producing means, means for intermittently discharging a predetermined quantity of liquid refrigerant into said evaporator, means for circulating an inert gas through said evaporator, and a liquid circulating drain including a U-shaped loop portion arranged to form a gas sealing liquid trap

connecting the gas inlet and outlet portions of said evaporator, the portion of said drain connected to the gas inlet portion of said evaporator being positioned to fill said U-shaped portion of said drain with liquid supplied to said evaporator from said intermittently operative discharge means.

9. An absorption refrigerating system comprising an inert gas circuit including an evaporator 10 and an absorber, a boiler, liquid conveying means connecting said boiler and said absorber for flow of absorbing liquid therethrough, means for liquefying refrigerant vapor generated in said boiler, liquid conveying means for conducting refrigerant liquid from said liquefying means to said evaporator, and means in said liquid refrigerant 15 conducting means for intermittently collecting the refrigerant liquid supplied thereto to alter the operation of the system and for thereafter discharging the collected liquid to allow normal 20 operation of the system to be resumed, said collecting means being included in said inert gas circuit, the arrangement being such that collection of a predetermined quantity of liquid refrigerant will block the flow of inert gas until such 25 collected liquid is discharged, and means arranged to convey liquid refrigerant from a part of said evaporator having a high refrigerant vapor concentration to a part of said evaporator 30 having a low refrigerant vapor concentration.

10. That method of producing refrigeration which includes the steps of intermittently supplying refrigerant liquid to an evaporating zone at a rapid rate, propelling an inert gas through 35 the evaporating zone to circulate the liquid but at a rate insufficient to evaporate all the liquid supplied thereto, recirculating unevaporated liquid from the gas outlet portion to the gas inlet portion of the evaporating zone, and evaporating 40 residue liquid refrigerant into the circulating inert gas during periods when no liquid is supplied to the evaporating zone.

ARNOLD D. SIEDLE.
